UNITED STATES PATENT OFFICE.

JOSEPH KILBURN PRIEST, OF NASHUA, NEW HAMPSHIRE.

HAIR-CLIPPING MACHINE.

SPECIFICATION forming part of Letters Patent No. 350,991, dated October 19, 1886.

Application filed April 29, 1886. Serial No. 200,527. (Model.)

To all whom it may concern:

Be it known that I, JOSEPH KILBURN PRIEST, a citizen of the United States, residing at Nashua, in the county of Hillsborough 5 and State of New Hampshire, have invented certain new and useful Improvements in Hair-Clipping Machines; and I do hereby declare the following to be a full, clear, and exact description of the invention, such as will enable 10 others skilled in the art to it which appertains to make and use the same.

My invention consists in certain novel constructions and combinations of parts in a hair-clipping machine, as will be hereinafter 15 described, and pointed out in the claims.

In the accompanying drawings, Figure 1 is a top view of my improved hair-clipper complete. Fig. 2 is also a top view, but with the outer portions of the handles broken away and 20 some of the upper parts removed in order to show the construction of the parts below. Fig. 3 is a side elevation of the machine as shown in Fig. 1. Fig. 4 is a back view of the same, with the handles partly broken away. Fig. 5 25 is a vertical section in the line $x-x$ of Fig. 1, the handles being partly broken away. Fig. 6 is a perspective view of the presser-plate of the clipper, and Fig. 7 is a perspective view of the same inverted. Fig. 8 is a perspective 30 view of the spring bridge-plate used above the presser-plate of the clipper. Fig. 9 is an enlarged sectional view showing the self-locking clamping device detached from the machine. Fig. 10 is a horizontal section in the line $z-z$ 35 of Fig. 9, and Fig. 11 is a horizontal section in the line $y-y$ of Fig. 9.

The letter A in the drawings represents a lower stationary toothed cutter-plate; B, an upper toothed sliding or reciprocating cutter- 40 plate; C and D, handles; E, a presser-plate; F, a bridge-spring plate, and G a clamp device.

The cutter-plate A has comb-shaped cutting-teeth a , and is attached to the handle C, 45 as will be seen. This handle C is provided with a thumb-loop, c , thumb-horn c' , and rest c'' of substantially the same construction as shown in my United States Patent No. 317,671.

At the fulcrum of the handles C and D a 50 cylindrical housing, c^3 , is formed on the handle C, which housing has a closed top and a central tubular bearing, c^4 , and by this con-

struction an annular space, c^5 , is formed, into which a spiral spring, H, is inserted. The upper end, h , Fig. 3, of this spring is inserted 55 into and held by a slot, c^6 , of the said housing. Two lugs, c^7 , are provided at the foot of the housing, and are fastened by means of headed screws a' to the cutter-plate A, thus firmly uniting it with the handle C. The lugs 60 c^7 are respectively set off laterally from the handle C and the housing on the right and left sides of the fulcrum of the said handle, so as to provide room for the handle D, as shown in the drawings. A tubular bearing, d^6 , is 55 formed on a horizontal portion, d , of the handle D, and fitted on a screw-pin or bolt, g , which has its lower or head end, g' , fitted into cutter-plate A, and secured thereby longitudinally, while it is laterally secured by means of 70 a key, a^2 . This bolt is thus made to serve as a key, a^2 . This bolt is thus made to serve as the fulcrum for the handle D. The tubular bearing d^6 , by being fitted into the tubular bearing c^4 of the handle C, becomes a support therefor, while it also serves for steadyng the 75 movement of the handle D.

The handle D is provided with a finger-loop, d^7 , and a forefinger-stop, d^8 , the same as in my Patent No. 317,671; but to the outer termination of the finger-loop a curved rest, d^9 , 80 is added, which renders the manipulation of the hair-clipper more convenient than the loop alone for certain operations of hair-cutting. Near the fulcrum of the handles a notch, d^10 , is provided on the handle D, into 85 which notch the lower end, h' , of the spring H is inserted, whereby the handle D is held away from the handle C. Instead of forming a notch, as d^11 , a projection may be provided for holding the spring. The horizontal flat portion d of 90 said handle is fitted beneath and between the housing c^3 and a loose washer, a^4 , next to the cutter-plate A, and it is allowed to move freely sideways between the lugs c^7 to the requisite extent for cutting. Said handle is also provided with an eccentrically-acting lug, d^5 , which moves with a snug lateral fit in a notch, b , of the upper cutter-plate, B. The upper cutter-plate, B, is provided with cutters b' , 95 similar to the cutters a , and with transverse 100 guide-slots b^2 , into which latter guide-pins a^2 , suitably provided on the cutter-plate A, are fitted, so as to produce a rectilinear motion of the cutter-plate B, parallel with the cutters

a of the cutter-plate A. A presser-plate, E, provided with a transverse downwardly-extended flange, *e*, and ledges *e'*, rests, by means of the flange *e*, upon the front portion of the 5 cutter-plate B, near the cutters *b*, while its rear portion rests, by means of its ledges *e'*, upon the lugs *c'*. Next to said ledges *e'* two curved flanges, *e''*, are provided on the presser-plate, which fit the round portions of the 10 lugs, and are held laterally in position by two angular projections, *c''*, of the said lugs, inasmuch as they are tightly fitted between the end surfaces of the flanges *e''*. The presser-plate E is also provided with an opening, *e''*, 15 which fits the outer surface of the housing *c'*, and thus, together with the opposite fit of the curved flanges *e''* on the lugs *c'*, longitudinal motion of said plate is rendered impossible. Upon the front portion of the presser-plate, 20 and extending nearly across the same, the triangular bridge-spring plate F rests by means of its vertical flange *f*. The rear portion of the bridge-spring plate F is provided with a lug or pin, *f'*, which rests in a shallow recess, *c''*, formed in the handle C. About its center the bridge-spring plate F is provided with hole *f''*, through which the upper extended end of the screw-bolt *g* passes. The 25 screw-thread of the bolt *g* is extended above the bridge-spring plate to the end of the bolt, and a nut, *g''*, and washer *g'''*, Figs. 3, 4, 5, and 10, are applied thereon, as shown. The nut *g''* is cylindrical, and is provided with either a tubular or solid milled head, *g''*, and 30 a body which has longitudinal slots *g''* terminating, preferably, in radial holes *g''*, formed in a thinned annularly-grooved portion, *g''*, of the body *g''*. The lower end surface, *g''*, of the nut is either spherical or conical, and rests in 35 either a spherical or conical depression, *g''*, of the washer *g'''*. The depression *g''* of the washer being more elongated or pointed than the surface *g''* of the nut, the slotted portion of the nut will become compressed around the bolt 40 *g* when the nut is screwed down sufficiently into the washer, and will thus be caused to grip the bolt very tightly and to become locked thereon so securely that it is not liable to become loosened during the operation of the hair-clipper, no matter how closely the two cutter- 45 plates are clamped together by the clamping device. The radial holes *g''* and groove *g''* render the slotted portion of the nut sufficiently elastic to insure an expansion of the body portion of the nut away from the screw-bolt *g* as soon as the nut is turned back far enough to 50 clear the washer. The exterior surface, *g''*, of the washer is made spherical or conical, in order to secure a central pressure and avoid 55 one-sided or unequal bearing upon the bridge-spring plate.

In the described hair-clipper I have provided a clamping device which is very effective, quick, and permanent. Effective, inasmuch as the pressure of the flange *f* equally distributes itself from end to end across the

presser-plate, this being due to the fact that the pin *f'* and flange form a triangular bridge-spring, and the force of the screw-bolt is applied through washer *g'''* about centrally of the 70 pin and flange *f*, and the washer, having no flat bearing on the spring-plate, will exert no more pressure on one side than on the other should the spring-plate yield unequally, and quick and permanent on account of the clamp-screw being in the center and provided with a self-locking thumb-button nut, which by one movement will effect the desired adjustment and become locked without the use of a wrench. I have also provided, by the construction shown, for the insertion of a larger and more powerful spring, H, 75 in a comparatively convenient manner. The use of extra bolts or screws for holding the presser-plate is dispensed with, and pressure upon the cutter-plates is rendered so yielding 80 that the cutters are saved from the danger of being broken should any unyielding substance accidentally get between them during the operation of the hair-clipper, said cutter-plates under such circumstances parting from each other so that the obstructions between them can be removed by the operator. The construction is also such that the spring-plate, presser-plate, and upper cutter-plate can be removed and replaced without disturbing the 85 spiral spring H, and whenever the operating parts become worn the washer *g'''* can be exchanged for a thicker one in order to avoid loose fitting of the handle D.

What I claim is—

1. The combination of the clamping and pressure screw-bolt *g*, fastened to and projecting up from the stationary cutter-plate A, the slotted nut *g''*, and the concave or conical washer *g'''*, with the movable cutter-plate B, presser-plate E, bridge-spring plate F, and stationary cutter-plate A, substantially as and for the purpose described.

2. The handle C, provided with the housing *c'*, having the flanges *c'*, annular chamber *c''* for the spring H, and tubular bearing *c''*, all fastened to the stationary cutter-plate A, in combination with the movable handle D, having a tubular bearing, *d''*, with horizontal flat portion *d*, upon which the tubular bearing *c''* bears, substantially as described.

3. The combination, with the handle C, of the housing *c'*, comprising chamber *c''*, tubular bearing *c''*, and outer slot, *c''*, the handle D, having notch *d'*, and the spring H, having upper end, *h*, and lower end, *h'*, substantially as and for the purpose described.

4. The combination of the housing *c'*, forming a tubular bearing, *c''*, for the tubular bearing *d''*, and the chamber *c''* for the spring H, 125 the handle D, having the tubular bearing *d''*, which is open at both its lower and upper ends, and is provided with the flat portion *d*, the cutter-plates A and B, screw-bolt *g*, extended up through and above the bearing *d''*, 130 the presser-plate E, the bridge-spring F, and a suitable pressure device applied on the bolt

g, substantially as described, and for the purpose set forth.

5. In a hair-clipping machine, the combination of the presser-plate E, having flanges *e* *e*², ledges *e*', and opening *e*³, the handle C, having lugs *e*¹, with projections *e*⁸, and the housing *e*⁵, having chamber *e*⁶ for the spring H, substantially as and for the purpose described.

In testimony whereof I affix my signature in the presence of two witnesses.

JOSEPH KILBURN PRIEST.
